UNITED STATES PATENT OFFICE

PHILIP C. TRAVER, OF LYNBROOK, NEW YORK, ASSIGNOR TO JAMAICA SEA AIRPORT, OF JAMAICA, NEW YORK

MOORING MAST

Application filed January 27, 1930. Serial No. 423,832.

This invention relates to improvements in mooring masts of the type used for anchoring and retaining aircraft of the lighter than air type, such as rigid dirigibles commonly known as zeppelins or semi-rigid airships.

An important object of the invention is to provide, in a manner as hereinafter set forth a mooring mast of the aforementioned character which embodies means for automatically anchoring the airship as it approaches the mast in order to facilitate securing same to the top of the mast.

Other important objects of the invention is to provide a mooring mast for airships embodying means whereby said airship may be moored thereto in such a manner that the necessity for the services of a great number of people is eliminated.

Further objects of the invention are to provide a mooring mast for airships which will be simple in construction, strong, durable, efficient in its use and which may be constructed at low cost.

All of the foregoing and still further objects and advantages of the invention will become apparent from a study of the following specification, taken in connection with the accompanying drawings, wherein like characters of reference designate corresponding parts throughout the several views, and wherein:

Figure 1 is a top plan view of a mooring mast construction in accordance with this invention,

Figure 2 is a view in side elevation thereof,

Figure 3 is a vertical sectional view taken substantially on the line 3—3 of Figure 1,

Figure 4 is a fragmentary vertical sectional view taken substantially on the line 4—4 of Figure 1,

Figure 5 is a fragmentary vertical sectional view taken substantially on the line 5—5 of Figure 1,

Figure 6 is a fragmentary view broken away in horizontal section substantially on the line 6—6 of Figure 5,

Figure 7 is a fragmentary vertical sectional view taken substantially on the line 7—7 of Figure 5,

Figure 8 is a detail view of the anchor.

Referring to the drawings in detail, the reference character 1 designates the upstanding mooring mast formed preferably of cementitious material and tapering from its bottom to its top. The mast 1 is mounted centrally on a circular base or foundation 2 having a conical upper surface 3, said foundation being embedded a suitable distance in the ground for the purpose of anchoring the same. The lower end portion of the mast 1 is formed hollow to provide a compartment or operating room 4 to which access may be had through a door 5 as seen in Figure 2.

The mast 1 terminates in a flat upper end and a bore or passage 6 extends centrally therethrough and communicates with the compartment or room 4. An angular tubular member 7 is mounted for rotation on the upper end of the mast and is provided with a bore which communicates with the bore 6 in said mast, as illustrated to advantage in Figure 3 of the drawings. Cable 8 passes through the bore in the member 7 and extends downwardly through the bore 6 of the mast 1 and is windable on a windlass 9 mounted for rotation in the compartment or room 4 of the mast.

The free end of the cable 8 is provided with a hook 10 the purpose of which will be presently set forth. A vertically disposed windlass 11 is mounted on the floor of the compartment or room 4 and, as illustrated to advantage in Figure 5 of the drawings, the windlass 11 may be operatively connected to an electric motor 12 disposed vertically in a compartment 13 provided in the bottom of the mast. If desired, the windlass 11 may also be manually rotated in a manner similar to the windlass 9.

A cable 14 is windable on the windlass 11 and is adapted to be selectively inserted through any one of the openings 15 extending through the wall of the mast adjacent said windlass 11. The free end of the cable 14 is also provided with a hook 16, the purpose of which will be more fully hereinafter set forth.

A series of spaced, radiating substantially V-shaped guide fingers or extensions 17 ex-

tends from the periphery of the base or foundation 2, as illustrated to advantage in Figure 1 of the drawings. A series of radially disposed inclined tunnels 18 are provided in the base or foundation 2 and have their outer ends communicating with the periphery of said foundation or base at a point between the adjacent inner ends of the guide fingers or extensions 17.

10 As clearly illustrated in Figure 6 of the drawings, the width of each of the tunnels 18 is the same as the width between the adjacent inner ends of the guide finger 17 and an inwardly swingable door or closure 19 is mounted therein.

The ceiling or upper wall of each tunnel is provided with a longitudinally extending slot 20 which is open at its outer end.

Suitable light 21 may be provided in the upper side of the base or foundation 2 and a light 22 may also be mounted in the angular tubular member 7 on top of the mast for the purpose of guiding airships and facilitating the mooring of same at night.

25 In use, as the airship which is designated by the reference numeral 23 nears the mast 1, a cable 24 is lowered therefrom, said cable being payed out from a suitable winding mechanism (not shown) usually carried by the airship. The free end of the cable 24 has secured thereto a comparatively heavy spherical anchor or drag 25 which is secured to said cable 24 through the medium of the stem or rod 26 having the ring 27 on its free end. As the airship approaches the mast, the anchor 25 drags along the ground and enters between adjacent pairs of the guide fingers or extensions 17 being guided thereby into the tunnel 18, said anchor pushing the inwardly swinging one way door 19 open as it enters the tunnel.

As illustrated to advantage in Figure 7 of the drawings, the stem 26 travels inwardly through the slot 20 in the upper wall or ceiling of the tunnel through which the anchor is travelling. It should be here mentioned that the upper marginal portion of the outer walls of the guide fingers or extensions 17 are provided with the outwardly extending beads or ledges 28, (see Figure 4) for the purpose of preventing the anchor 25 from being pulled or dragged transversely across one of said guide fingers.

If desired, the beads or ledges 28 may be provided with a metallic protective casing (not shown) to prevent same from being broken off. After the anchor 25 enters one of the panels 18, the hooks 10 and 16 of the cables 8 and 14 respectively are connected to the coupling element 29 and the anchor 25 is detached from said coupling element 29. The cable 14 is then payed out from the windlass 11 and simultaneously the cable 8 is wound on the windlass 9. Also simultaneously with this operation the windlass in

the airship 23 is actuated in a manner to wind the cable 24 thereon for the purpose of taking up slack which would otherwise occur in said cable 24 when the free end thereof is elevated to the top of the mooring mast.

When the mooring operation has been completed, the several cables are in the position which is best illustrated in Figure 2 of the drawings, if desired the anchor 25 may now be removed from the tunnel 18 in which it is disposed, as said anchor is of no further use until the airship leaves the mast.

It is believed that the many advantages of a mooring mast constructed in accordance with this invention will be understood, and although the preferred embodiments of the invention are as illustrated and described, it is to be understood that changes in the details of construction may be had which will fall within the scope of the invention as claimed.

Having thus described my invention, what I claim as new is:

1. A mooring mast of the character described comprising a circular base upon which the mast is centrally mounted, said base having a series of radiating anchor receiving tunnels opening at its periphery, and radially extending guide fingers extending from the peripheral wall of the base at opposite sides of the outer ends of the tunnels and adapted to direct an anchor thereinto.

2. A mooring mast of the character described comprising a circular base upon which the mast is centrally mounted, said base being provided with a series of radially disposed anchor receiving tunnels opening at its periphery and a series of spaced, substantially V-shaped guide fingers radiating from the peripheral wall of the base and having their inner ends disposed closely adjacent the open ends of the tunnels and adapted to direct an anchor thereinto.

3. A mooring mast of the character described comprising a circular base upon which the mast is centrally mounted, said base being provided with a series of radially disposed anchor receiving tunnels opening at its periphery, a series of substantially V-shaped spaced guide fingers radiating from the peripheral wall of the base and having their inner ends disposed closely adjacent the opposite sides of the open ends of the tunnels in a manner to direct an anchor thereinto, outwardly extending ledges on the sides of the guide fingers to engage with the anchor in a manner to prevent same from being dragged transversely over said fingers from the space between the same.

4. A mooring mast of the character described comprising a circular base upon which the mast is centrally mounted, said base being provided with a series of radially disposed anchor receiving tunnels opening at its periphery, a series of substantially V-shape spaced guide fingers radiating from

the peripheral wall of the base and having their inner ends disposed closely adjacent the opposite sides of the open ends of the tunnels in a manner to direct an anchor thereinto, outwardly extending ledges on the sides of the guide fingers to engage with the anchor in a manner to prevent same from being dragged transversely over said fingers from the space between the same, and an inwardly opening one-way door hingedly mounted in the outer end portion of each tunnel.

5. A mooring mast of the character described comprising a circular base upon which the mast is centrally mounted, said base being provided with a series of radially disposed anchor receiving tunnels opening at its periphery, a series of substantially V-shaped spaced guide fingers radiating from the peripheral wall of the base and having their inner ends disposed closely adjacent the opposite sides of the open ends of the tunnels in a manner to direct an anchor thereinto, outwardly extending ledges on the sides of the guide fingers to engage with the anchor in a manner to prevent same from being dragged transversely over said fingers from the space between the same, and an inwardly opening one-way door hingedly mounted in the outer end portion of each tunnel, said tunnels being disposed coaxially with the mast and being provided, in their upper wall, with a longitudinal extending slot for the reception of an anchor coupling stem, said slots open at their outer ends.

6. A mooring mast of the character described comprising a circular base upon which the mast is centrally mounted, an angular tubular arm swivelly mounted on the upper end of the mast, a compartment in the lower end portion of the mast, said mast being further provided with a bore extending vertically therethrough and communicating, at one end, with the compartment and at its upper end with the arm, a windlass mounted for rotation in the compartment of the mast, a cable windable on the windlass and extending through the bore and through the arm, the walls of the compartment being provided with transverse openings, a windlass mounted for rotation within the compartment adjacent the opening, a cable windable on the windlass extending through one of the openings and means on the outer end of each of the cables for detachably coupling same to the anchoring cable of an airship.

7. A mooring mast of the character described comprising a circular base upon which the mast is centrally mounted, said base having formed therein a series of radially disposed inclined tunnels opening at its periphery and having longitudinally extending slots in their upper walls, said slots being open at their outer ends, an anchor adapted for disposition in the tunnels, a coupling stem

secured to the anchor and adapted to project through the slots in the upper walls of the tunnels, means for detachably coupling said stems to the anchoring cable of an airship, radiating fingers projecting from the peripheral wall of the base on opposite sides of the open end of the tunnels in a manner to direct the anchor thereinto, the mast being provided with a compartment in its lower portion and being further provided with a vertically extending bore communicating with the compartment and with the upper end of the mast, a tubular angular arm swivelly mounted on the upper end of the mast and communicating with the bore therein, a horizontally disposed windlass mounted for rotation in the compartment, a cable windable on the windlass extending through the bore and the arm, a vertically disposed windlass mounted for rotation in the compartment, a cable windable on the vertical windlass and extending outwardly through the wall of the compartment, and means on the free end of the cable for detachably coupling same to the free end of the airship anchoring cable.

In testimony whereof I affix my signature.
PHILIP C. TRAVER.
